M. C. LOWREY
COMBINED MOP AND WRINGER

1,733,418

Filed Feb. 24, 1928

UNITED STATES PATENT OFFICE

MONROE C. LOWREY, OF POTEAU, OKLAHOMA

COMBINED MOP AND WRINGER

Application filed February 24, 1928. Serial No. 256,668.

This invention relates to certain novel improvements in self wringing mops and consists of the novel and inexpensive construction hereinafter described and claimed.

5 The salient object of my invention is to provide a self wringing mop which will embody a handle construction having the component parts thereof arranged in telescopic relation whereby they may be reciprocated 10 relative to each other to facilitate manipulation of the mop.

Another object of the invention is to provide a self wringing mop in which the mop cloth may be formed in a continuous belt like 15 structure which may be mounted between two members carried by the above mentioned telescopically arranged handle construction such that the mop cloth may be brought under tension between the parts adapted to carry 20 the same.

A further object of the invention is to arrange the device in such a manner that when the mop cloth is tensioned between the members carrying the same, a pair of rollers 25 may be passed thereover so as to extract the water therefrom in order to substantially dry the same.

Other objects will appear hereinafter.

The invention consists in the novel combination and arrangement of parts to be hereinafter described and claimed.

The invention will be best understood by reference to the accompanying drawings, showing the preferred form of construction 35 and in which:

Fig. 1 is a front elevational view of a self wringing mop embodying a preferred form of construction for my invention;

40 Fig. 2 is a side elevational view of the device illustrated in Fig. 1;

Fig. 3 is a detail view taken substantially on the line 3-3 on Fig. 1;

Fig. 4 is a detail view taken substantially 45 on the line 4-4 on Fig. 1;

Fig. 5 is a view depicting a modified form of construction for the members adapted to extract the water from the mop cloth;

50 Fig. 6 is a view looking in at the lower side of the device depicted in Fig. 5; and

Fig. 7 is a sectional detail view taken substantially on the line 7-7 on Fig. 6.

My improved construction for self wringing mops includes a novel handle formation in which a substantially tubular sleeve 10 is 55 provided through which a rod 11 is adapted to extend so as to be reciprocal therein. The tubular sleeve 10 has a reduced opening 12 formed at the lower end thereof so as to define a shoulder 13 therein. At the lower 60 end of the rod 11 a rod 14 is secured which is adapted to be of a restricted size relative to the rod 11. A spring 15 is disposed to extend between the lower end of the rod 11 and the shoulder 13 and said spring is disposed around the rod 14. The spring 15 is 65 adapted to urge the rod 11 upwardly for a purpose to be brought forth hereinafter. At the upper end of the rod 11 a suitable hand grip 16 is provided.

70 Adjacent the lower end of the sleeve 10 a substantially U-shaped member 17 is mounted which includes a loop portion 18 that is adapted to be disposed around and clamped to the sleeve 10 at a point removed 75 from but juxtaposed to the lower end of the sleeve 10. The leg portions of this member 17 are directed upwardly and extend through a plate 18 which is suitably secured to the sleeve 10 and which serves to increase the rigidity 80 of the member 17. At the lower end of the rod 14 a plate 19 is secured and a substantially U-shaped member 20 is fastened to this plate 19 and is arranged such that the leg portions thereof extend upwardly or better in the same direction as the leg portions of the member 17. The mop cloth 21 is adapted to be formed into substantially a continuous belt like member that is adapted to be extended between the bight portion of 90 the member 17 and the plate 19.

Adjacent the upper end of the sleeve 10 an opening 22 is provided in the rod 11 adjacent the lower end of the handle construction 16. Secured to the rod 11 so as to extend across 95 the recess 23 is a resilient clip 24 which has a boss 25 formed thereon. A finger portion 26 is provided on the upper end of the resilient clip 24. When the rod 11 is disposed within the sleeve 10 in the manner depicted in Figs. 100

1 and 2 the plate 19 and the member 18 are spaced apart a distance sufficient to bring the mop cloth 21 under tension and when the parts are so disposed the boss 25 is arranged within 5 the opening 22 so as to hold the parts in this relative position.

A handle 27 is reciprocally mounted on the sleeve 10 and carries an outwardly extending plate 28 at the lower end thereof. Substantially 10 V-shaped members 29 and 30 are directed through spaced apart openings 31 provided in the plate 28 and the bight portions of the members 29 and 30 are disposed on the upper side of said plate 28 as clearly shown 15 in Figs. 1 and 2. The lower ends of the legs of the members 29 and 30 extend through the ends of shafts 32 and 33 which extend across the mop cloth in the manner best illustrated 20 in Fig. 1. Rollers 34 and 35 are rotatably mounted on the shafts 33 and 32 and these rollers are preferably made of rubber or other 25 analogous material. Suitable clips 36 and 37 are mounted on the members 29 and 30 and embrace the legs thereof. By moving these 30 clips 36 and 37 along the members 29 and 30 toward the shafts 32 and 33 said shafts and the rollers carried thereby are forced into 35 tighter engagement with the mop cloth 21. Thus when the members 18 and 19 are spaced 40 apart so as to bring the mop cloth 21 under tension and when the members 36 and 37 are positioned on the members 29 and 30 such that the rollers 34 and 35 are forced into engagement with the mop cloth 21 the handle 27 45 may be reciprocated along the sleeve 10 so as to move said rollers 34 and 35 across the mop cloth 21 and inasmuch as said rollers will be under tension the water in the mop cloth 21 will be squeezed or extracted therefrom.

40 After the mop cloth 21 has been dried in the manner heretofore described the handle 27 is moved upwardly so as to dispose the rollers 34 and 35 adjacent the member 17. Then the finger portion 26 is engaged so as to bend the resilient clip 24 into the recess 23 and thus the boss 25 is retracted from the opening 45 22. The rod 11 is then moved rearwardly until the plate 19 engages the lower end of the sleeve 10. This frees the mop cloth 21 from 50 tension and said mop cloth is freely suspended from the structure and may therefore be used in the manner well understood in the art for cleaning purpose and for withdrawing water from a surface and the like.

55 In Figs. 5, 6, and 7, I have depicted a modified form of construction for the wringing members or rollers. Herein the sleeve 38 is reciprocally mounted on the sleeve 10 and carries brackets 39 and 40 which have downwardly 50 extending legs that are suitably secured to the mid-points of laterally extending members 41 and 42. As illustrated in Fig. 7, a slot 43 is provided at the end of the member 41 and a shaft 44 is mounted therein. The 60 end of the member 41 is screw threaded so as

to receive an interiorly screw threaded cap 45. A spring 46 extends between the end of the cap and shaft 44 and acts on the shaft 44 to force said shaft toward the inner end of the slot 43. A similar construction is provided at 65 each end of the member 41 and at each end of the member 42. The shaft 41 extends between one end of the member 42 and the member 41 and a shaft 47 extends between the other ends of these members and rollers 34' and 35' 70 similar to the rollers 34 and 35 are mounted on these shafts. By running in the caps 45 the rollers 34' and 35' may be moved toward each other and the position of the caps 45 will regulate the tension of the springs 46 and 75 therefore the tension exerted on the shafts 41 and 47 and therefore the relative distance and tension between the rollers 34' and 35'. The 80 mop cloth will be distended in the manner heretofore described and by reciprocating the sleeve 38 along the sleeve 10 the rollers 34' and 35' will be passed across said mop cloth so 85 as to extract the water therefrom.

It is apparent from the foregoing description that I have provided a device which may 90 be expeditiously arranged so as to distend the mop cloth in a manner such that squeezing members may pass there over so as to extract water therefrom. The device is also arranged in such a manner that the means for distending the mop cloth may be expeditiously operated and locked in a position such that the 95 hereinafter mentioned squeezing process may be readily carried out.

While I have illustrated and described the 100 preferred form of construction for carrying my invention into effect, this is capable of variation and modification, without departing from the spirit of the invention. I, therefore, do not wish to be limited to the precise 105 details of construction set forth, but desire to avail myself of such variations and modifications as come within the scope of the appended claims.

Having thus described my invention what 110 I claim as new and desire to protect by Letters Patent is:

1. In a device of the character stated a relatively elongated sleeve, a rod member extended through said sleeve and being of greater length than said sleeve, a handle portion on one end of said rod member, a recess in said rod member adjacent said handle portion, a yieldable clip mounted on said rod member and extending across said recess, an outwardly projecting lug on said clip, a supporting member on said sleeve at the end thereof opposite the end associated with the handle on said rod, a supporting member on the end of said rod opposite said handle, a substantially belt-like mop cloth directed around said supporting members said rod member being adapted to be extended from said sleeve whereby to dispose said supporting members in space apart relation to place 120

5 said mop cloth under tension, said outwardly projecting lug on said resilient clip being adapted to be disposed in an opening in said sleeve to hold said rod member in said extended position, a second sleeve reciprocal over said first named sleeve, a plate carried by said sleeve, substantially V-shape supporting members carried by said plate and extended past said supporting member on said 10 sleeve, rod members extending between the outer end portions of said V-shape supporting members, roller members carried by said rod members adapted to be disposed in engagement with said tension mop cloth, and means adapted to act on said V-shape members for 15 holding said rollers in engagement with said cloth.

2. In a device of the character stated, a sleeve, a rod mounted for movement through said sleeve, a supporting member carried by said sleeve, a supporting member carried by said rod, a substantially continuous belt like mop cloth mounted on said supporting members, said rod being movable through said sleeve whereby said supporting members may 25 be spaced apart to place said cloth under tension, means for holding said supporting members in said spaced relation, a sleeve having a plate mounted thereon, substantially 30 V-shaped members suspended from said plate, rollers mounted at the lower free ends of said V-shaped members, and means slidably along said V-shaped members adapted to urge said rollers into engagement with said tensioned 35 mop cloth whereby said rollers may be moved thereacross as said second named sleeve is reciprocated along said first named sleeve.

In testimony whereof I affix my signature.
MONROE C. LOWREY.
